UNITED STATES PATENT OFFICE

153,732

DESIGN FOR A PORTABLE GRANDSTAND
FRAME

John F. Roney, Los Angeles, Calif., assignor to
Safway Steel Products, Inc., Milwaukee, Wis.,
a corporation of Wisconsin

Application January 30, 1948, Serial No. 144,150

Term of patent 14 years

(Cl. D54—1)

To all whom it may concern:

Be it known that I, John F. Roney, a citizen of the United States, residing at Los Angeles, in the county of Los Angeles and State of California, have invented a new, original, and ornamental Design for a Portable Grandstand Frame, of which the following is a specification, reference being had to the accompanying drawing, forming part thereof.

Figure 1 is a perspective view of a portable grandstand frame, showing my new design;

Figure 2 is a side elevational view of the device illustrated in Figure 1; and

Figure 3 is a top plan view of the device illustrated in Figure 1.

I claim:

The ornamental design for a portable grandstand frame, substantially as shown.

JOHN F. RONEY.
